UNITED STATES PATENT OFFICE

IRVING B. MOORE, OF WATERTOWN, MASSACHUSETTS, ASSIGNOR OF ONE-HALF TO
JOHN R. SIBLEY, OF WEST ROXBURY, MASSACHUSETTS

BUMPER

Application filed February 7, 1931. Serial No. 514,086.

This invention relates to bumpers and bumperettes for motor vehicles and has for its object the production of devices of this character which will be capable of withstanding severe shocks and subsequently return the various elements thereof to their normal positions.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings

Figure 1 represents a plan of a bumper for motor vehicles embodying the principles of the present invention.

Figure 2 represents an enlarged section on line 2, 2, on Fig. 1.

Figure 3 represents a transverse section on line 3, 3, on Fig. 2.

Figure 4 represents a rear elevation of a portion of the bumper, and

Figure 5 represents a front elevation of a portion of said bumper.

Similar characters indicate like parts throughout the several figures of the drawings.

In the drawings, 10 is a straight flat bar secured to the vehicle by members 11.

In front of the bar 10 and spaced therefrom is another bar 12.

The front bar 12 has projecting from the rear face thereof a plurality of threaded projections 13 which may be formed integral with said bar or riveted thereto as shown at 13a.

Each projection 13 is adapted to enter and be secured to a cup-shaped member 14 having secured thereto one end of a helical spring 15.

The opposite end of each spring 15 is secured to another cup-shaped member 16.

The bar 10 has a plurality of threaded openings therein each to receive a screw plug 17, the forward end of which is adapted to enter and be threaded to one of the cup-shaped members 16.

Each screw plug 17 is provided with a depression 18 therein by which said plug may be rotated.

Between the bar 10 and each cup-shaped member 16 is a split washer 19 which is adapted to prevent accidental rotation of the plug 17.

It will be noted that the cup-shaped members 14 and 16 are permanently secured to the opposite ends of the helical spring 15.

Both bars 10 and 12 have coverings of rubber 20, 21 and these coverings may be of any color to harmonize with the color of the vehicle itself.

The front face of the covering 21 may have moulded therein a block 22 of a different color and of any desired shape, and this block may have distinguishing characters 23 therein.

For instance, these designating characters in the covering may be the name of the vehicle, the name of the owner, or any other desired characters, thereby giving a more ornamental appearance to the bumper.

Interposed between the bars 10 and 12 and surrounding each pair of cup-shaped members 14, 16 and the connecting helical spring 15, is a tubular member 24 of resilient material such as rubber, preferably colored like the coverings 20, 21.

In assembling the various elements of the bumper, the cup-shaped members 14 are threaded to the projections 13.

The tubular members 24 are then placed over the cup-shaped members 14, 16 and spring 15.

With these elements thus installed, the front bar 12 with the other elements secured thereto is then placed in position adjacent the bar 10 and the screw plugs 17 are threaded to the several cup-shaped members 16.

The rubber coverings to the bars 10 and 12 and particularly the covering of the bar 12

will prevent the marring of a vehicle when coming into contact therewith.

Should the impact be considerable the spring 15 will be compressed and likewise the rubber tubes 24, thus preventing injury to the vehicle itself.

These interposed resilient members 15, 24, are capable of moving sidewise to some extent when the bumper is hit at an angle and will 10 return to their normal positions as soon as the vehicles are separated.

This makes a very simple construction of vehicle bumper which will sustain heavy shocks.

15 The various elements may be assembled very readily and manufactured at a minimum expense.

It is believed that the operation and many 20 advantages of the invention will be understood without further description.

Having thus described my invention, I claim:

1. In a vehicle bumper, two parallel bars, a plurality of helical springs between said 25 bars and secured at opposite ends thereto, and a tube of resilient material surrounding each spring.

2. In a vehicle bumper, two parallel bars, a tubular covering of rubber for the front 30 bar, and a plurality of resilient members between said bars and secured at opposite ends thereto.

3. In a vehicle bumper, two parallel bars, tubular coverings of rubber for said bars, and 35 a plurality of resilient members between said bars and secured at opposite ends thereto.

4. In a vehicle bumper, two parallel bars, a plurality of oppositely disposed projections 40 on said bars, a helical spring for each pair of projections, cup-shaped members at the opposite ends of said spring and secured thereto, said cup-shaped members fitting over said projections, and means for locking said cup-shaped members to said projections.

45 5. In a vehicle bumper, two parallel bars, a plurality of oppositely disposed threaded 50 projections on said bars, a helical spring for each pair of projections, and cup-shaped members at the opposite ends of said spring and secured thereto, said cup-shaped members being threaded to said projections.

55 6. In a vehicle bumper, two parallel bars, a plurality of oppositely disposed projections 60 on said bars, the projections in the rear bar being removable, a helical spring for each pair of projections, cup-shaped members at the opposite ends of said spring and secured thereto, said cup-shaped members fitting over said projections, and means for locking said cup-shaped members to said projections.

65 7. In a vehicle bumper, two parallel bars, a plurality of oppositely disposed projections 70 on said bars, the projections in the front bar being riveted thereto, a helical spring for each pair of projections, cup-shaped members

at the opposite ends of said spring and secured thereto, said cup-shaped members fitting over said projections, and means for locking said cup-shaped members to said projections.

8. In a vehicle bumper, two parallel bars, a plurality of helical springs between said bars and secured thereto, and a tube of resilient material surrounding each spring.

9. In a vehicle bumper, two parallel bars, coverings of rubber for said bars, a plurality of resilient members between said bars and secured at opposite ends thereto, and enclosures of resilient material surrounding said resilient members.

10. In a vehicle bumper, two parallel bars, a plurality of oppositely disposed projections on said bars, the projections in the rear bar being threaded thereto, a helical spring for each pair of projections, cup-shaped members at the opposite ends of said spring and secured thereto, said cup-shaped members being threaded to said projections, and means for locking said cup-shaped members to said projections.

Signed by me at 746 Old South Bldg., Boston, Massachusetts, this 5th day of February, 1931.

IRVING B. MOORE.
